(57) **CLAIM**

The ornamental design for a bracket, as shown and described.

DESCRIPTION

FIG. 1 is a perspective view of a bracket showing our new design;

FIG. 2 is a front view of the bracket;

FIG. 3 is a side view of the bracket;

FIG. 4 is a top view of the bracket; and,

FIG. 5 is a bottom view of the bracket.

The broken lines showing an attachment piece are for illustrative purposes only and form no part of the claimed design.
